UNITED STATES PATENT OFFICE

FRANK D. TALBERT, OF LOS ANGELES, CALIFORNIA

PIN RESETTING APPARATUS

Application filed October 18, 1930. Serial No. 489,514.

This invention relates to an improvement in a cue pin game and the principal object is to provide a ten pin resetting apparatus for the game that is semi-automatic in its action of resetting the ten pins after they have been displaced by a ball driven by a cue over the ball course.

In other words the game is played by arranging a ball at the forward end of a ball course and then driving it with considerable force toward ten pins that are pivotally suspended above the course adjacent its rear end, which when struck releases latches that permit the ten pins to move to elevated positions, and an object in playing the game is to strike and release as many pins as possible with one ball. The game can be played exactly like the game of bowling except that in this game the ball is driven by a cue, preferably an ordinary billiard cue.

The principal object of the invention is to provide a pin resetting apparatus that is semi-automatic in its action of resetting the pins so they can be struck by a ball. To that end I provide means actuated by a motor for moving the pins back into a set position.

This means includes a switch in circuit with the motor that is closed by means actuated by the pins when struck by a ball so as to release the latches that hold the pin supporting levers in horizontal position, which levers when released fall on the trigger bar and close the switch so that the motor will start to reset the pins when an operator at the forward end of the table actuates a push button switch for that purpose; and also connected to the pin resetting apparatus is an arm on a crank shaft which at a predetermined time or just after the pins have been reset opens said switch to stop the motor.

Another object of the invention is to provide a pin resetting apparatus that is easy to construct, assemble and operate and which resets the ten pins with great speed so that little or no time is lost in playing the game as the pins are reset almost instantly with the actuation of the push button switch at the forward end of the ball course.

Features of invention are shown in the construction, combination and arrangement

of parts whereby a pin resetting apparatus is provided that in addition to being semi-automatic in the action of starting the motor, resetting the pins and then stopping the motor is also durable and effective in use.

Other objects, advantages and features of invention may appear from the accompanying drawings, the subjoined detailed description and the appended claims.

The accompanying drawings illustrate the invention, in which:

Fig. 1 is a side view of a cue pin table to which the pin resetting apparatus is connected but not visible from a side elevation, showing a portion of the side rail broken away to show a ball arranged on the ball course in position to be struck by a billiard cue.

Fig. 2 is an enlarged fragmental cross section on line 2—2, Fig. 1, showing a pin resetting apparatus constructed in accordance with this invention.

Fig. 3 is an enlarged fragmental section on line 3—3, Fig. 2, showing the detailed construction of a knife switch that is arranged to be automatically opened and closed to start and stop the motor.

Fig. 4 is a section on the line 4—4, Fig. 2, on a slightly reduced scale showing the ten pins arranged over the ball course and also showing a plan view of the levers for supporting the pins.

Fig. 5 is a diagrammatic plan view of the cue pin table showing the pin resetting apparatus connected to a motor and electrical means for actuating the motor.

Fig. 6 is an enlarged fragmental section on line 6—6, Fig. 4, showing the detailed construction of one of the latches employed for holding the pins on the ball course so they can be struck by a ball.

Fig. 7 is a fragmental section on line 7—7, Fig. 6, showing the pivotal connection of the ten pins to their supporting levers.

Fig. 8 is a fragmental section on the line 8—8, Fig. 4, with a major portion of the ten pins and levers omitted for the sake of clearness in the drawings and semidiagrammatically illustrating the pin resetting apparatus.

Fig. 9 is a view analogous to Fig. 8 with the ten pins raised above the ball course and also showing its reset position by dotted lines.

Fig. 10 is a slightly enlarged side view of the pin resetting apparatus shown in Figs. 8 and 9.

Fig. 11 is an enlarged fragmental section on line 11—11, Fig. 10, with parts slightly modified as to size and form and also showing the detailed construction and mounting of the pin resetting bar and associated parts.

The cue pin table 15 is provided with the usual ball course 16 over which a ball 17 can be driven by a billiard cue 18 toward the suspended ten pins 19 at the foot of the course; also a back stop 20, and ball runway 21 that leads back to a ball basket 22 at the forward end of the table. The table preferably is supported on legs 23 at about the usual height of a billiard table, and also has the usual side rails 24 to keep the balls on the course.

All of the foregoing parts are old and well known in the art and are shown only for illustrating the purpose of the pin resetting apparatus.

The rear end of the table is provided with a box frame 25 adjacent the rear end of the course 16 that supports the ten pins 19 and which also encloses the pin resetting apparatus.

A bearing rod 26 is secured in the sides of the box frame 25 and adjacent their top ends and front edges on which the blocks 27 have their upper ends pivotally mounted, and extending through the lower ends of the block 27 and at right angles to the rod 26 are the cylindrical levers 28 that are adjustable through the blocks by means of set screws 29. The levers 28 are spaced apart and also spaced away from the box frame 25 by washers 126, as best indicated in Fig. 4.

Weights 30 are adjustably mounted on the rear ends of the levers 28 to overbalance the ten pins 19 and move them from a set to elevated positions, and these weights are held in adjusted position by means of the set screws 31.

The levers 28 are normally held in horizontal position by latches 32. These latches include the slidable members 33 that are slidably mounted in a latch supporting bar 34 extending crosswise in the top of the box frame 25. The members 33 are arranged in recesses 35 in the latch supporting bar 34, and have their beveled ends 36 extended through plates 37 secured to the sides of the latch bar. The ends 36 are held yieldingly extended by springs 38 engaging the latch bar and annular shoulders 39 on the latch members 33, as best shown in Fig. 6. The other members 40 of these latches are slidably extended through the upper ends of the block 41 adjustably mounted on the levers 28 by set screws 42. The members 40 have ends 43 beveled oppo-

site to the ends 36 of the other members so they can easily slide by one another when the pins 19 are being reset, but cannot pass one another when moved in the opposite direction, except when the members 40 are actuated by a means that will now be explained.

The ten pins 19 have rods 44 extending from their upper ends to which pivot balls 45 are secured as by brazing and these balls are loosely mounted in the pivot cups 46 at the forward end of the levers 28 so that when the pins are struck by a ball they have practically universal swinging movements so they can hit one another.

In other words if a ball is driven over the course so as to strike one of the pins centrally it will drive the pin in a swing arc so as to hit other pins back of it, but if the pin is hit off center it will be driven sidewise in one direction or the other.

The rods 44 are extended for some distance above the balls 45 and terminate in eyelets 47 to which one end of a strong string or cord 48 can be secured; and if desired the parts 48 can be semiflexible wires.

The other ends of the cords 48 are secured to eyelets 49 in the forward ends of the members 40 so that when the cords are pulled by swinging movement of the pins they will move the members 40 against the tension of the light springs 50 to release the latch members 33, 40 from one another, so that the weights 30 can lift the ten pins 19 from the ball course.

In other words the latches 32 are arranged to hold the levers 28 in horizontal positions so the pins 19 can be struck by a ball driven over the course; and when the pins are struck they release their respective latches 32 by pulls on the cords 48 so that the weights 30 can then move the levers from a horizontal to an inclined position and thereby lift the pins from the course.

While the idea of lifting the ten pins from a ball course after they have been struck by a ball is relatively old the specific means employed for mounting the ten pins and holding the levers in a horizontal position are thought to be new.

The means for resetting the pins includes a resetting bar 51 arranged under the rear ends of the levers 28 and crosswise to the table, and secured to the ends of this cross bar are the sleeves 52 that are slidably mounted on the vertical guide rods 53, and preferably this bar carries a shock absorbing plate 54, as best shown in Fig. 11.

This shock absorbing plate is provided with guide pins 55 that extend downward through holes 56 in the bar 51, and interposed between the bar and plate and surrounding the guide pins 55 are springs 57 that absorb the shock when the falling weights 30 cause the levers 28 to strike heavily against the plate 54.

The bar 51 is pivotally connected by links 58 with crank arms 59 on the crank shaft 60 that is mounted in the stands 61 secured to the bottom of the table 15, as best shown in Fig. 2.

Secured to the shaft 60 is a worm gear 62 that is driven by a worm 63 on the shaft of the motor 64 so that when the motor is driven the crank shaft through its connection to the bar 51 will slide it upon the guide rods 53 and engage the plate 55 with the undersides of the inclined levers 28 and move them into horizontal position; and when so moved the latch members 33, 40 will slide by one another and latch so as to hold the levers in horizontal positions until released again by a driven ball striking the ten pins.

Also extended crosswise under the levers 28 is a trigger bar 65 having one end pivotally mounted in one end of the box frame 25 and the other end suspended by a light spring 66, and this bar carries a link 67 that is pivotally connected to one arm of a bell crank 68 pivotally mounted in the upper end of a post 69.

The bell crank 68 has an insulation block 70 on its other arm that is adapted to throw the knife 71 of the knife switch 72 into engagement with the spaced spring contacts 73, 74 to close the circuit between the motor 64 and a battery 75 when the bell crank is actuated so that the motor will be actuated whenever the push button switch 76 at the front end of the cue pin table is also closed.

The circuit connecting the battery 75 to the motor and switches is diagrammatically illustrated in Fig. 5, and as seen therein a wire 77 connects one side of the battery with a spring contact 78 that is adapted to be manually moved by the push button 79 into engagement with the spring contact 80.

The contact 80 is connected by a wire 81 to the spring contact 73 arranged adjacent the spring contact 74 which latter is connected by a wire 82 with the motor 64 that is also connected by a wire 83 with the other side of the battery 75 so that when both of the switches 72 and 76 are closed the motor 64 will be driven to rotate the crank shaft 60 and through the means heretofore described reset the levers 28 that support the ten pins over the ball course in position to be struck by a ball. The contacts 73, 74 are mounted on the insulating post 100, as best shown in Fig. 3.

When any of the levers 28 falls and strikes the trigger bar 65 the knife 71 is thrown by the bell crank 68 between the spring contacts 73, 74 and is held there until thrown out of engagement with these contacts by a cam arm 84 on the shaft 60. In other words, when the switch 72 is closed the motor 64 will start as soon as the switch 76 at the forward end of the table is also manually closed.

The switch 76 is not closed until a player

completes a play which may include one or more shots of the ball 17 at the ten pins. The game is usually played with two balls, one shot to follow the other if the first shot has not affected all of the ten pins so as to release their latches 32. In other words a player may shoot the first ball and strike only a few of the pins, after which he can use the second ball to strike any of the pins remaining over the course in position to be struck, the object being to strike the pins and release as many of the latches as possible in a play.

At the end of each play if a pin has been struck so as to release a latch the switch 72 will be closed by the means heretofore described so that as soon as the push button switch 76 at the forward end of the table is closed the motor will start to reset all of the pins that have been struck and moved out of a set position; and in resetting these pins the crank shaft 60 makes but one revolution at the end of which the cam arm 84 engages the knife 71 and moves it out of engagement with the contacts 73, 74 to stop the motor.

In operation the game is played in a manner similar to bowling, except that in this instance the ball or balls are driven over the course with a cue instead of being propelled by hand; and in the play it is possible to strike the forward pin so as to release the latches of all ten of the pins or make a strike.

In other words all of the plays made in bowling can be made in this cue pin game. It is possible to make very high, intermediate or low scores according to the skill of the player.

By means of my pin resetting apparatus I avoid any arduous labor and save considerable time in resetting the pins. Heretofore it was necessary to pull a hand lever to reset the pin which, through its distant connection with the pin resetting mechanism required considerable strength to accomplish a resetting of the pins and also required considerable time to effectively operate the lever. By my means the pins are reset in less than two seconds after the push button switch is closed and without any labor, which makes the game highly interesting and pleasant to play and also develops great skill in the players.

I claim as my invention:

1. A pin resetting apparatus including a cross bar arranged under a pivotally mounted lever for moving it from an inclined to a horizontal position to reset a pin over a ball course, a crank shaft arranged under said bar, links pivotally connecting said crank shaft to said cross bar, and an electric motor for rotating said shaft.

2. A pin resetting apparatus including a cross bar arranged under a pivotally mounted lever for moving it from an inclined to a horizontal position to reset a pin over a ball

course, guides at the ends of said cross bar, a crank shaft arranged under said bar, links pivotally connecting said crank shaft and cross bar, an electric motor for rotating said shaft, and means actuated by said lever and shaft for starting and stopping said motor.

3. A pin resetting apparatus including a cross bar arranged under a pivotally mounted lever for moving it from an inclined to a horizontal position to reset a pin over a ball course, vertical guide rods adjacent the ends of said cross bar, sleeves secured to the ends of said cross bar that are slidably mounted on said rod, a crank shaft arranged under said cross bar, links pivotally connecting said crank shaft and cross bar, and an electric motor for rotating said crank shaft.

4. The combination set forth in claim 3 and means actuated by said lever and shaft for starting and stopping said motor.

5. A pin resetting apparatus including a cross bar arranged under a lever for moving it from an inclined to a horizontal position to reset a pin over a ball course, vertical guide rods adjacent the ends of said cross rods, sleeves secured to the ends of said cross bar that are slidably mounted on said rods, a crank shaft, links pivotally connecting said crank shaft and cross bar, an electric motor for rotating said shaft, a switch in circuit with said motor, a trigger bar arranged to be engaged by said lever for closing said switch to start said motor, and an arm on said crank shaft for opening said switch to stop said motor.

6. A pin resetting apparatus including a cross bar arranged under a plurality of pivotally mounted levers for moving them from an inclined to a horizontal position to reset their pins over a ball course, vertical guide rods adjacent the ends of said cross bar, sleeves secured to the ends of said cross bar that are slidably mounted on said rods, a crank shaft, links pivotally connecting said crank shaft and cross bar, an electric motor for rotating said crank shaft, a switch in circuit with said motor, a trigger bar arranged to be engaged by one or more of said levers when they fall from a horizontal to an inclined position for closing said switch to start said motor, and an arm on said shaft for opening said switch to stop said motor.

7. The combination set forth in claim 6 and a battery and a manually operated push button switch at the head of the ball course in circuit with said motor and battery for the purpose specified.

8. In a pin resetting apparatus the combination with a pivotally mounted lever, a pin pivotally connected to one end of said lever, a latch for normally holding said lever in a horizontal position so said pin is suspended adjacent a ball course in position to be struck by a ball, means whereby said latch is released when said pin is struck by a ball so that said

lever will move from a horizontal to an inclined position to lift said pin from the ball course, of a resetting bar arranged under said lever, and electrically operated means for actuating said resetting bar to move said lever from an inclined to a horizontal position to reset said pin.

9. In a pin resetting apparatus the combination with a pivotally mounted lever, a pin pivotally connected to one end of said lever, a latch for normally holding said lever in a horizontal position so said pin is suspended adjacent a ball course in position to be struck by a ball, means whereby said latch is released when said pin is struck by a ball so that said lever will move from a horizontal to an inclined position to lift said pin from the ball course, of a resetting bar arranged under said lever, guide rods adjacent the ends of said resetting bar, sleeves on the ends of said resetting bar that are slidable on said rods, and electrically operated means for moving said resetting bar to move said lever from an inclined to a horizontal position to reset said pin.

10. In a pin resetting apparatus the combination with a pivotally mounted lever, a pin pivotally connected to one end of said lever, a latch for normally holding said lever in a horizontal position so said pin is suspended adjacent a ball course in position to be struck by a ball, means whereby said latch is released when said pin is struck by a ball so that said lever will move from a horizontal to an inclined position to lift said pin from the ball course, of a resetting bar arranged under said lever, guide rods adjacent the ends of said resetting bar, sleeves on the ends of said resetting bar that are slidable on said rods, and electrically operated means for moving said resetting bar to move said lever from an inclined to a horizontal position to reset said pin.

11. In a pin resetting apparatus the combination with a pivotally mounted lever, a pin pivotally connected to one end of said lever, a latch for normally holding said lever in a horizontal position so said pin is suspended adjacent a ball course in position to be struck by a ball, means whereby said latch is released when said pin is struck by a ball so that said lever will move from a horizontal to an inclined position to lift said pin from the ball course, of a resetting bar arranged under said lever, guide rods adjacent the ends of said resetting bar, sleeves on the ends of said resetting bar that are slidably mounted on said rods, a crank shaft, links pivotally connecting said shaft to said resetting bar, and a motor for revolving said shaft to actuate said resetting bar to reset said pin.

110

115

120

125

130

135

12. In a pin resetting apparatus the combination with levers pivotally mounted above a ball course and having pins pivotally mounted at their forward ends and latches connected with said pins arranged to normally hold said levers in horizontal positions so their pins can be struck by a ball passing over said course and weights at the rear ends of said levers for moving them from horizontal to inclined positions when said latches are released by said pins when struck by a ball, of a resetting bar arranged under and adjacent the rear ends of said levers, a crank shaft, links connecting said shaft to said resetting bar, and an electrical motor for actuating said crank shaft.
13. In a pin resetting apparatus the combination with levers pivotally mounted above a ball course and having pins pivotally mounted at their forward ends and latches connected with said pins arranged to normally hold said levers in horizontal positions so their pins can be struck by a ball passing over said course, and weights at the rear ends of said levers for moving them from horizontal to inclined positions when said latches are released by said pins when struck by a ball, of a resetting bar arranged under and adjacent the rear ends of said levers, a crank shaft, links connecting said shaft to said resetting bar, and an electrical motor for actuating said crank shaft.
14. In a pin resetting apparatus the combination with levers pivotally mounted above a ball course and having pins pivotally mounted at their forward ends and latches connected with said pins arranged to normally hold said levers in horizontal positions so their pins can be struck by a ball passing over said course, and weights at the rear ends of said levers for moving them from horizontal to inclined positions when said latches are released by said pins when struck by a ball, of a resetting bar arranged under and adjacent the rear ends of said levers, vertical guide rods arranged adjacent the ends of said resetting bar, sleeves secured to the ends of said resetting bars that are slidably mounted on said guide bars, a crank shaft, links pivotally connecting said shaft and resetting bar, an electric motor for rotating said shaft, a switch in circuit with said motor, a trigger bar actuated by said levers when moved from horizontal to inclined positions for closing said switch to start said motor, and an arm on said shaft for opening said switch to stop said motor when the pins have been reset.
15. In a pin resetting apparatus the combination with a ball course having ten pins supported in position to be struck by a ball passing over said course and means to move said pins to an elevated position when struck by a ball, of a resetting bar, a crank shaft pivotally connected to said bar, and an elec-
- trical motor for rotating said crank shaft to reset said ten pins.
16. The combination set forth in claim 15 and a switch in circuit with said motor that is normally open when said ten pins are in a set position, and automatic means for closing said switch when said ten pins are struck by a ball and are moved out of a set position.
17. The combination set forth in claim 15, and a shock absorber plate carried by said resetting bar for the purpose specified.
- In testimony whereof I affix my signature.
